UNITED STATES PATENT OFFICE.

FRED MAUE, OF SHAMOKIN, PENNSYLVANIA, ASSIGNOR TO J. H. & C. K. EAGLE, INC.,
A CORPORATION OF PENNSYLVANIA.

HANDING-IN MECHANISM.

Application filed February 10, 1923. Serial No. 618,366.

To all whom it may concern:

Be it known that I, FRED MAUE, a citizen of the United States, residing at Shamokin, in the county of Northumberland and State of Pennsylvania, have invented certain new and useful Improvements in Handing-In Mechanism, of which the following is a specification.

The present invention relates to mechanism for handing-in the warp threads, in the operation of passing the same through the loops or eyes in the heddle or harness wires.

It is the general practice to employ two operators in drawing-in the warp threads through the heddle eyes. One operator is positioned upon one side of the heddle, while the assistant operator is positioned upon the opposite side. The assistant operator alternately selects a warp thread from the two bunches of warp threads, which are previously crossed, and hands each selected warp thread to the drawing-in operator, who draws the same through the eye of the heddle.

Attempts have heretofore been made to dispense with the assistant operator, for handing-in the selected warp thread.

In accordance with the present invention, the construction of such a machine is greatly simplified, and its operation rendered easier. The machine is operated by a single pedal, and no operating parts are mounted upon any of the lease rods of the lease frame. The stationary clamp for holding the ends of the two bunches of warp threads is dispensed with, while the ends of the bunches are maintained separate, and are held within separate clamps or holders, which are shifted laterally with respect to each other. The device is therefore entirely separate from the lease frame, and is therefore rendered entirely portable, and may be quickly shifted to different positions with respect to the lease frame, or readily moved from one lease frame to another.

In the accompanying drawings forming a part of this specification and in which like numerals are employed to designate like parts throughout the same,

Figure 1 is a perspective view of handing-in mechanism embodying my invention,

Figure 2 is a central vertical transverse sectional view through the mechanism,

Figure 3 is a longitudinal sectional view

through the upper portion of the mechanism, parts in elevation, taken on line 3-3 of Figure 2,

Figure 4 is a plan view of one of the clamps,

Figure 5 is a side elevation of the same,

Figure 6 is a side elevation of the upper portion of the mechanism, showing the clamps or holding elements in one position, with the selected warp thread released, and,

Figure 7 is a similar view with the next selected warp thread released, and the clamps shifted to the other extreme position,

Figure 8 is a view of the gear and its connection with the reciprocating rod.

In the drawings, wherein for the purpose of illustration is shown a preferred embodiment of my invention, the numerals 10 and 11 designate lease rods, included in the usual lease frame. The numeral 12 designates longitudinal bars of the heddle or saddle frame, and 13 the heddle wires, provided with the usual eyes 14, through which is passed a hook or element 15, employed in drawing-in the warp threads. This is the usual construction, as is well known in the art, and which is illustrated in Patent No. 1,067,602.

The handing-in mechanism, constituting the present invention, embodies a base 16, which is unattached to the floor, and renders the entire mechanism portable. Formed upon the upper side of the base is a vertical sleeve 17, having a vertical tubular standard 18, clamped therein. This standard receives a reciprocating rod 19, which is cylindrical. This rod does not turn upon its longitudinal axis, but is slidable longitudinally within bearings 20 and 21, clamped within the tubular standard 18. The lower end of the rod 19 carries upon one side thereof a trunnion or pivot 22, operating within an elongated slot 23, formed in a crank or arm 24.

This crank or arm is clamped upon a rock shaft 25, journaled in a bearing 26, rigid upon the base 16. The rock shaft 26 has a pedal 27 rigidly secured to its free end. It is obvious that the operator may place her foot upon the pedal 27, and by swinging the same in opposite directions, cause the rod 19 to reciprocate.

The numeral 28 designates a horizontal casing or support, carrying a depending

sleeve 29, preferably integral therewith, which is clamped to the tubular standard 18. The casing or support 28 is arranged horizontally, and is parallel with the rock shaft 25.

The numerals 30 and 31 designate shifting boxes or carriers, which are slidable longitudinally within the casing or support 28, and are held spaced from each other by 10 a horizontal strip 32, attached to the upper end of the casing 28. The upper end of the casing 28 is otherwise open while its bottom is closed. The box or carriers 30 and 31 are equipped with depending bases 32', provided with longitudinal racks 33, arranged upon their inner faces. These racks engage the opposite sides of a gear 34, having a central opening, slidably receiving the upper end of the rod 19. The upper portion 20 of this rod is provided with a spiral groove 35, and the gear 34 is provided with an inwardly projecting pin or stud 36, which enters the spiral groove 35. The gear 34 is free to rotate but cannot move vertically, and for this purpose, open brackets 36', are arranged upon opposite sides of the upper end of the rod 19, within the casing 28, and have openings 37', into and through which the gear 34 projects. The upper and lower 30 faces of each bracket 36' are provided with curved race-ways 38, receiving bearing balls 39, engaging within circular race-ways 40, formed in the upper and lower faces of the gear 34.

35 Mounted within the boxes or carriers 30 and 31 are clamps or holding elements 41 and 42, receiving the ends of the two bunches 43 and 44, of the warp threads. These clamps are preferably identical, and may be of any suitable construction. For the purpose of illustration, clamps are shown, embodying sides 45, hinged together at 46. The free ends of the clamps are detachably connected by bolts 47 or the like. If desired, 45 a strip of fibrous material 48 may be held within the clamps, in engagement with the warp threads. The clamps are mounted within the boxes or carriers, and are held therein against upward displacement, by tying elements 49, detachably connected with the boxes or carriers 30, and extending over the clamps, as shown.

50 It is thus seen that the clamps are removably held within the boxes or carriers. It is obvious that the clamps have sufficient frictional engagement with the warp threads in the bunches to hold them against accidental displacement, but will permit of the selected warp thread being withdrawn from the clamp, by the operator, without disturbing the remaining warp threads.

55 In operation, the bunches 43 and 44 of the warp threads, are passed upon one side of the upper lease rods 10, and these bunches are then passed upon opposite sides

of the lower lease rod 11. The bunches are then crossed, at a point A, below the lower lease rod 11, and are thereby interlaced. The bunches extend downwardly from this point and are held within the two clamps 70 or holding elements, as shown. It is thus seen that the clamps or holding elements not only serve to shift the bunches laterally, but also serve to hold the same against longitudinal displacement, during the shifting 75 operation. As clearly illustrated in Figure 6, the first warp thread B to the right, belonging in bunch 44, is left free, while the remaining warp threads are crossed and interlaced. The warp thread designated by 80 B, may now be drawn through the eye 14 of the heddle. When this is done, the operator shifts the pedal 27 whereby the box 31 is shifted to the right, and box 30 to the left, as shown in Figure 7. This 85 movement will release the warp thread C of the bunch 43, while the remaining warp threads are retained interlaced. This operation is continued until each warp thread in turn is selected and released, and drawn 90 through the eye of the heddle.

95 It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described my invention, I 100 claim:

1. Handing-in mechanism for warp threads, comprising a substantially vertical support, a shaft mounted upon the support to move longitudinally thereof, a pedal arranged near the lower end of the support and having an operative connection with the shaft to effect its longitudinal movement, a casing mounted upon the upper end of the support, reciprocating elements mounted within the casing and having means for engaging with bunches of warp threads, rack bars extending longitudinally of the reciprocating elements and connected therewith, a gear arranged between the rack bars to simultaneously shift them in opposite directions, and means whereby the longitudinal movement of the rod serves to turn said gear.

2. Handing-in mechanism for bunches of warp threads, comprising a base, an upstanding tubular standard carried by the base, a reciprocating rod mounted within the tubular standard, a pedal arranged near the base and having connection with the rod to effect its reciprocating movement, a support 120 mounted upon the upper portion of the tubular standard, reciprocating elements mounted upon the support and having means for engaging with the bunches of warp threads, rack bars carried by the reciprocating ele- 125

- ments, a gear arranged between the rack bars and engaging them, and means for effecting a threaded connection between the reciprocatory rod and said gear.
- 5 3. Handing-in mechanism for bunches of warp threads, comprising a support, a gear mounted upon the support, a pair of reciprocatory elements having means for engaging with the bunches of warp threads, rack bars carried by the reciprocatory elements for engaging with the gear, a reciprocatory rod, means for effecting a threaded connection between the rod and gear, and a manually operated element to move the reciprocatory 10 rod.
- 15 4. Handing-in mechanism for bunches of warp threads, comprising a base, a tubular standard carried thereby, a casing mounted upon the upper end of the tubular standard, a reciprocatory rod within the tubular standard, a pedal mounted near the base and having connection with the rod to reciprocate it, a pair of carriers mounted to reciprocate within the casing, rack bars arranged beneath the carriers and attached thereto and extending longitudinally thereof, a gear arranged beneath the carriers between the rack bars and engaging therewith, means for effecting a screw threaded connection between the gear and rod, and means mounted upon the carrier for engaging the bunches of warp 20 threads.
- 25 5. Handing-in mechanism for bunches of warp threads which are passed upon opposite sides of a lease rod and crossed, comprising a support, a pair of reciprocatory carriers mounted upon the support and provided with rack bars, a gear mounted upon the support between the rack bars and engaging therewith, manually operated means to turn the gear in opposite directions, and a pair of clamps secured to the carriers and 30
- 35 engaging the ends of said bunches to hold them against displacement and to shift the same laterally.
- 40 6. Handing-in mechanism for bunches of warp threads, which are passed upon opposite sides of a lease rod and crossed, comprising a support, a pair of reciprocatory carriers mounted upon the support and provided with longitudinally extending rack bars, a gear mounted upon the support between the rack bars and engaging the rack bars, an operating shaft having screw threaded engagement with the gear, means to move the shaft longitudinally in opposite directions, and clamps mounted upon the carriers to engage with the ends of the bunches to hold them and shift them laterally.
- 45 7. Handing-in mechanism for bunches of warp threads which are crossed and passed upon opposite sides of a lease rod, comprising a tubular standard, a reciprocatory rod extending longitudinally within the standard and provided near its upper end with a spiral groove, a crank connected with the lower end of the rod to shift it longitudinally, a pedal connected with the crank to move it in opposite directions, a casing mounted upon the upper end of the tubular standard, carriers slidably mounted within the casing and having longitudinally extending rack bars, a gear rotatable upon the upper end of the rod and having an extension entering the spiral groove, means to hold the gear against movement longitudinally of the rod, and clamping devices removably mounted upon the carriers to engage with the ends of said bunches and to shift said 50 55 60 65 70 75 80 85 ends laterally.

In testimony whereof I affix my signature.

FRED MAUE.
